UNITED STATES PATENT OFFICE.

CAPPELLI DOMENICO, OF NEW YORK, N. Y.

KEY-OPERATED LOCK.

1,133,943.

Specification of Letters Patent. Patented Mar. 30, 1915.

Application filed September 9, 1913. Serial No. 788,953.

To all whom it may concern:

Be it known that I, CAPPELLI DOMENICO, a subject of the King of Italy, residing at New York, in the county of New York and State of New York, have invented new and useful Improvements in Key-Operated Locks, of which the following is a specification.

The general object of the invention is to improve the construction of key operated locks in point of simplicity and general efficiency. And to these ends the invention resides in providing a plurality of latch bolts and adapting one of these to be projected and retracted by a key, and to control the projection and retraction of the other latch bolt.

Other objects will appear and be better understood from that embodiment of my invention of which the following is a specification, reference being had to the accompanying drawings, forming part hereof in which:—

Figure 1 is a front elevation of the device in use. Fig. 2 is an elevation on an enlarged scale looking into the lock from the face opposite to that shown in Fig. 1 and with the guard plates removed and also showing the position of the parts in unlocked position. Fig. 3 is a plan of the lock showing the door to which it is connected in section, and disclosing the means for fastening the lock and keeper to the door and door frame. Fig. 4 is a view similar to Fig. 2 but on a reduced scale and showing the position of the parts when the lock is locked and also showing the guard plates and the relative positions of the key holes. Fig. 5 is a vertical cross section on the line 5—5 of Fig. 2. Fig. 6 is a detail perspective of the main bolt. Fig. 7 is a detail perspective of the tumbler latch for the main bolt.

The lock forming the subject-matter of the present invention is intended for use with safes, receptacles, or with any structure where the employment of a permutation lock may be found necessary. In the embodiment shown the lock is constructed so that access to the parts thereof with a key, may be had from only one face of the door to which the lock is applied, but it will be obvious from what will hereinafter appear, that if so desired, the lock may be readily adapted to permit of access thereto with a key from either face of the door.

In the present instance, the lock casing

is indicated by 5, the tumblers by 6, the tumbler springs by 7, the supplemental bolt by 8, the main bolt by 9, the main bolt lock by 10, the main bolt tumbler latch by 11, the main bolt latch spring by 12, the main bolt retractor spring by 13, the latch bolt by 14, the latch bolt spring by 15, the hub by 16, the latch bolt lock by 17, the latch bolt spring by 18, the latch bolt guides by 19—19, the spindle by 20, the knobs or operating handles by 21—21, the inner guard plate by 22, the outer guard plate by 23, the key post by 24, the key by 25, the key hole slots by 26 and 27, and the casing for the main bolt lock by 28.

The casing 5 is formed of metal and in the present instance is shown as arranged on the inner face of the door 29, to which it is attached by means of tie bolts, one of which is shown in Fig. 3 and indicated by 30, which pass through lugs 31—31 suitably connected to the upper and lower side walls of the casing and through a face plate 32 forming one end wall of the casing and counter-sunk in the front end of the door 29. The casing is additionally secured to the door by the presence of a plate 33 which bears on the face plate 32 and on the front wall of the casing 5, the outer surface of this plate being flush with the side of the door as shown in Fig. 3. The plate 32 is suitably connected to the door by screws (not shown). The plates 32 and 33 have openings to permit the passage of the bolts 8 and 9 from the casing 5 into the keeper 34. The supplemental bolt 8 is arranged above the bolt 9 and is supported by a stud in the form of a screw 35 which passes through a longitudinal slot 36 in the said bolt 8.

The tumblers 6 are carried by the stud 35 and are arranged so as to control the movement of the bolt 8, said tumblers for this purpose having the usual detents 37 and the longitudinal slots 38 which accommodate the laterally projecting stud 39 carried by the bolt 8. The wards 40 of the key 25 will, of course, be so proportioned as to lift the various tumblers the required amount during the turning of the key to bring the slots of the tumblers into alinement with the stud, whereby, to permit of the longitudinal movement of the bolt 8. The said bolt 8 and the bit of the key will, of course, each be so adapted to the other as to permit of the key moving the bolt longitudinally when

the wards have disengaged the tumblers from the stud 39, and the key turned.

The main bolt 9 is retained in the casing by a pin 41 which passes through a longitudinal slot 42 in the said bolt and is suitably connected to the front wall of the casing 5. The outer end of this pin 42 is surmounted by a head in the form of a nut 43. The said bolt 9 is also adapted to the bit 10 of the key 25 and arranged so as to be operated successively to the bolt 8 upon the turning of the key.

Referring now to Fig. 2 the bolt 8 has a depending end portion 44 which interfits 15 with a notch in the inner end portion of the bolt 9 when the parts are positioned as shown in Fig. 2. Referring more particularly to this position of the parts it will be seen that when the bolt 8 is moved outwardly by the key 25, it will carry with it the bolt 9 but when retracted or moved inwardly from projected position it will have no effect whatever on the movement of the said bolt 9.

25 The main bolt tumbler latch 11 is mounted for pivotal movement on a stud in the form of a screw 45. This tumbler latch 11 is formed with a lateral extension in the form of a tooth 46 and an elevated platform 47 and is arranged in such relation to the bolt 9 that upon initial outward movement of the said bolt under corresponding movement of the bolt 8, the tooth 46 will pass into a notch or detent 48 in the bolt 9 when the said bolt is projected by the bolt 8, and thereby lock the said bolt 9 in projected position.

When the parts are positioned as shown in Fig. 2, the projecting of the bolts 8 and 9 is effected by turning the key in a counter-clockwise direction and through an arc of about forty-five degrees. Now the distance through which the upper bolt travels during this turning movement of the key is equal 45 to the distance between the inner and intermediate detents in the tumblers 6 so that at the end of such movement on the part of the bolt 8 the stud 39 will be in the intermediate detents of the tumblers 6 and the bolt 8 locked against longitudinal movement. Now if the turning of the key be continued in a counter-clockwise direction, the ward thereof upon entering the sweep 49 in the upper side of the bolt 9, will bear 50 on the platform 47 of the tumbler latch 11 and depress the said tumbler latch until the tooth 46 thereof moves out of the notch or detent 48. But further turning movement of the key in a counter-clockwise direction 55 will effect contact between the ward thereof and the side of the sweep 49, whereupon the key will tend to retract the bolt 9, but this tendency will be resisted by the bolt 8 which is now locked by the tumblers 6 and interlocked with the bolt 9 through the depend-

ing end portion 44. Consequently after the projecting of the bolts 8 and 9 and the turning of the key for about forty-five degrees, the said key must be turned in a clockwise direction in order to restore the key to its 70 first position and this turning of the key in a clockwise direction will have the effect of retracting the bolt 8. Now it will be remembered that the bolt 9 is projected so that if instead of withdrawing the key from the lock the turning of the key be continued in a clockwise direction and until the bit enters the detent 50, then further turning of the key in a clockwise direction will effect a further projecting of the bolt 9 into 80 the keeper 84. This second movement on the part of the bolt 9 will effect the tensioning of the spring 13 by the stud 51 carried by the bolt 9.

The main bolt lock 10 is herein shown as 85 formed of an angular-shaped piece of spring steel one end of which is connected to the front face of the casing 5 by a pin 52. The free end portion of this lock carries a laterally extending pin 53 which extends through an opening in the front face of the casing 5 and bears on the bolt 9. The length of the pin 53 is such that the spring body portion of the lock will be flexed and thereby tensioned when the end 90 of the pin bears on the bolt, as shown in Fig. 2. Referring now to the last-named figure, 54 indicates an opening in the bolt 9 which is adapted for receiving the pin 53 and the position of the opening in the bolt 9 is such that the said opening will move into alignment with the pin 53 when the bolt 9 is projected a second time by the turning 95 of the key in a clockwise direction as previously described. Remembering now that 100 when the parts are positioned as shown in Fig. 2, the spring body portion of the lock 10 will be tensioned, it is obvious that when the opening 54 moves into alignment with the pin 53 the pin will pass into the opening 110 under the action of the spring body portion of the lock 10 and thereby hold the said bolt 9 against inward movement by the spring 13. After the second projecting movement is imparted to the bolt 9 by the 115 key 25 the turning of the latter in a counter-clockwise direction and into contact with the tumblers and the bolt 8, will project the latter, whereupon the parts will assume the position shown in Fig. 4. Inasmuch as the 120 detent 50 is wider than the detent 49 the key upon moving the bolt 8 to the position shown in Fig. 4 may be turned in a counter-clockwise direction and to the position shown in Fig. 2, at which time it may 125 be removed from the lock casing and leave the parts positioned as shown in Fig. 4 and locked inasmuch as the pin 53 on the lock bolt 10 enters the opening 54 in the bolt 9 and holds the said bolt in a projected posi- 130

tion. When the key is introduced into the lock for the purpose of retracting the bolts from the position shown in Fig. 4 the key is first turned in a clockwise direction, whereupon the bit will pass through the detent 50 and depress the tumbler latch 11 and move until the wards raise the tumblers 6 and the bit withdraws the bolt 8. Then the turning of the key is continued in a clockwise direction until the bit thereof is in alinement with a lateral projection 55 on the spring body portion of the lock 10. Referring now to Figs. 2 and 4, this projection 55 passes through an opening made to receive it in the front face of the casing 5 and when the pin 53 is in the opening 54 of the bolt 9 the inner surface of this projection is flush or substantially so with the inner surface of the front face of the casing 5. Here it may be stated that the bit extends a trifle beyond the end of the tubular shank of the key 25 so that when the bit is in alinement with the projection 55 as just described, the said bit will upon the application of hand pressure to the key and in the direction of the length of the same, operate to spring the lock 10 outwardly and withdraw the pin 53 from the opening 54, whereupon the bolt 9 will be retracted under the action of the spring 13 until the notch 48 thereof moves into alinement with the tooth 46 of the tumbler latch 11 at which time the tumbler latch will automatically engage with the bolt 9 under the action of its spring 12. The position of the parts will now be the same as when the bolt 9 was initially projected by the key and the bolt 8 retracted by the key, so that when the key is turned in a clockwise direction from a position where the bit is in alinement with the projection 55 the said bit will enter the sweep 49, depress the tumbler latch 11 and retract the bolt 9 to the position shown in Fig. 2 after which the key may be restored to the position shown in Fig. 2 and withdrawn from the lock.

The latch bolt 14 is slidingly fitted in the guides 19-19 and its inner end portion is upturned as indicated at 56, and forms a bearing for the tail piece 16 which is connected in the ordinary manner to the spindle 20. Referring now to Figs. 2 and 4 the hub 16 is a double-ended structure and by virtue of this and the upturned end portion 56 of the latch bolt 14 the engaging end 57 of said latch bolt will be withdrawn when the spindle is turned in a clockwise or counter-clockwise direction by the knob 21. The end portion 58 of the latch bolt spring 15 passes through a recess portion in the latch bolt 14 and is arranged so as to be tensioned when the latch bolt is retracted, and operates in the ordinary manner to restore the

latch bolt to its normal position when the knob 21 is released.

65

The latch bolt lock 17 is connected to a spindle 59 which is turnably mounted in the front face of the casing 5 and surmounted by a knob or operating handle 60. The said lock 17 is constructed with an elongated body portion 61 and is so disposed that when the said body portion is turned into the horizontal it will pass behind the engaging end portion 57 of the latch bolt and by thus lying in the path of movement of the said latch bolt prevent the inward movement thereof. The spring 18 serves as a means for holding the lock 17 when the same is positioned as shown in Figs. 2 and 4 and out of the path of movement of the latch bolt, and also when the said lock is adjusted into the path of the latch bolt.

70

The guard plate 22 bears upon posts 62-62 in the casing 5 and secured by screws 63 which pass through the said plate and screwed into the post 62. The guard plate 23 bears on posts 64-64 arranged in the casing 5. The posts 64 are longer than the posts 62 so that when the guard plate is positioned and secured by suitable screws (not shown) which pass through the guard plate and screw into the posts, the said guard plate 23 is spaced from the guard plate 22 as shown in Fig. 5. The key post 24 extends through the guard plates 22 and 23 and a semi-circular guide 65 partially surrounds the key hole 26 of the guard plate 23 and also the post 24 and operates to guide the tubular shank of the key of the post 24. The key hole 26 in the guard plate 23 is arranged in angular relation to the key hole 27 in the guard plate 22. Thus the provision of the guard plates and the angular relation of the key holes will defeat any ordinary attempt to pick the lock.

105

What is claimed as new is:

In a key operated lock the combination of a main bolt adapted to be operated by a key, and a bolt for holding said main bolt in a projected position, means engageable by the key for releasing the main bolt from the holding bolt, a supplemental bolt also adapted to be operated by the key, said main and supplemental bolt having engageable parts whereby the main bolt is moved to projected position when the supplemental bolt is moved to a similar position by the key and whereby the supplemental bolt is moved to retracted position when the main bolt is moved to retracted position by the key.
